(57) **CLAIM**

The ornamental design for a rolling container device, as shown and described.

DESCRIPTION

FIG. 1 is a perspective view of a rolling container device according to my design;

FIG. 2 is a left side view of the design of FIG. 1;

FIG. 3 is a right side view of the design of FIG. 1;

FIG. 4 is a front view of the design of FIG. 1;

FIG. 5 is a rear view of the design of FIG. 1;

FIG. 6 is a top view of the design of FIG. 1; and,

FIG. 7 is a bottom view of the design of FIG. 1.

The broken lines in the figures are included for the purpose of illustrating environment and form no part of the claimed design.
